(57) **CLAIM**

The ornamental design for a bottle, as shown and described.

DESCRIPTION

FIG. 1 top plan view showing my new design;

FIG. 2 is a front elevational view thereof;

FIG. 3 is a rear elevational view thereof; and,

FIG. 4 is a right side elevational view thereof, the left side being a mirror image except for the lower portion of the sidewall showing a portion of the contoured bottom.

The broken line showing of the pour spout is included to show environment and forms no part of the claimed design.
